UNITED STATES PATENT OFFICE.

GEORGE T. SMALLWOOD, OF WASHINGTON, DISTRICT OF COLUMBIA.

SYSTEM FOR BURNING OIL.

Application filed January 20, 1923. Serial No. 613,930.

To all whom it may concern:

Be it known that I, GEORGE T. SMALLWOOD, a citizen of the United States, residing at Washington, in the District of Columbia, 5 have invented certain new and useful Improvements in Systems for Burning Oil, of which the following is a specification.

The present invention relates to means for burning oil or other liquid fuel, the primary object being the provision of an apparatus by which the supply of fuel and of water can be regulated to a nicety in order to get the most effective results in combustion.

15 A further and important object is to provide a burner as a part of the apparatus, which burner is water-jacketed in a manner to protect it against quick destruction from heat, and at the same time provide means 20 for delivering moisture to the combusting gases so as to effect complete combustion and thus eliminate carbon deposit.

25 A further and important object is to provide means whereby the air supply for supporting combustion may either be atmospheric air, or in other words air unmixed with a gaseous fuel or a carburetted air may be employed.

30 Embodiments of the invention are illustrated in the accompanying drawings, wherein:

35 Figure 1 is a view somewhat diagrammatic in its character of the fuel and water supply means, showing the same mounted for furnishing such fuel and water to the burner or burners of a boiler.

Figure 2 is a view in elevation of the level-determining containers and is taken on the line 2-2 of Figure 1,

40 Figure 3 is a sectional view on the line 3-3 of Figure 2,

Figure 4 is a view in elevation of one of the valve-operating floats employed in the containers illustrated in Figures 2 and 3.

45 Figure 5 is a rear elevation of the valve operated by such float.

Figure 6 is a side elevation of the valve shown in Figure 5,

50 Figure 7 is an end elevation of the valve seat member,

Figure 8 is a vertical sectional view through the preferred embodiment of the burner structure,

Figure 9 is a detail sectional view of part of the spreader head.

In order to make the entire apparatus clear, it is probably best to first describe the burner structure, and considering the preferred embodiment illustrated in Figure 8, a combustion chamber 15 is provided, having a cylindrical and upwardly tapering side wall 16, forming an open top 17. This chamber is also provided with a bottom 18, preferably having an upstanding flange 19, into which the lower end of the cylindrical side wall 16 is arranged. The bottom is provided with a central depending extension 20. Surrounding the combustion chamber is a water jacket, comprising a cylindrical side wall 21, having an inturned top 22 provided with a central circular opening 23 that is in register with the open top of the combustion chamber. The top 22 overlies the top edge of the cylindrical side wall 16 of the combustion chamber, and is provided with depending positioning and retaining lugs 24. The top edge of the cylinder wall 16 is serrated, as illustrated at 25, providing open ports 26 affording communication between the top of the water jacket and the top of the combustion chamber. The water jacket is provided with a bottom plate or disk 27, preferably threaded to the cylindrical side wall 21, packing 28 being interposed between the two. The bottom 27 is beneath and spaced from the bottom 18 of the combustion chamber. As a consequence, it will be noted that the combustion chamber is not only surrounded with a water jacket, but that said water jacket 90 extends beneath the bottom.

95 A water supply pipe 29 is connected to the bottom 27, and opening into the lower portion of the water jacket supplies water thereto. The tubular extension 20 of the combustion chamber bottom 18 is threaded through the water jacket bottom 27, and screwed upon the lower projecting end of said extension is a coupling 30, the whole forming a fuel chamber 31 that extends 100 across the lower portion of the water jacket, and depends below said bottom 27. Connected to the coupling 30 is an oil or liquid fuel supply pipe 32, preferably threaded into one side of said coupling, the other side 105 also having a port 33 which may be em-

ployed for the connection of the pipe 32, according to the position of the burner. This other opening 33 is closed by a detachable plug 34 and may be employed as a 5 clean-out by the removal of said plug.

Extending upwardly and centrally through the fuel chamber 31 is a tubular stem 35. The upper end portion is surrounded by a protecting sleeve 36 that is 10 threaded into the extension 20. Said sleeve is provided with a plurality of fuel outlet ports 37 communicating with the chamber 31 and opening into the combustion chamber 15 above the bottom 18 thereof. The stem 15 35 projects above the sleeve 36, and detachably mounted thereon is a spreader head 38. The head is preferably composed of a composition of asbestos and fire clay or other 20 heat-resisting material. This head is held 25 in place by a pin 39 projecting from one side of the stem and engaging in a bayonet slot 40, formed internally in the neck 41 of said head 38. The neck 41 is provided with a plurality of radial ports 41^a opening 30 through the stem 35, and the head is provided with a plurality of divergent air outlet ports 42, and said head being circular in form, as illustrated in Figure 10, serves as a spreader or deflector in the central portion 35 of the combustion chamber. The lower end of the stem 35 has screwed thereto a T-coupling 43, one end of which is open to provide an inlet 44 for atmospheric air. This 40 inlet is controlled by a weighted flap valve 45 having an operating rod 46 extending therefrom. The other end of the coupling receives a supply pipe 47 leading from the outlet end of a vertical carburetter casing 48 that is located alongside the burner, 45 though this carburetter may be placed in any desired location, so long as its supply connection is in the pipe 32. The supply to this carburetter casing is by a pipe 49 connected to its lower end, and connected to the pipe 32.

The preferable internal construction of the carburetter is illustrated in Figure 11. It is provided with an Archimedes screw partition 50 forming a tortuous passageway 50 from the bottom to the top, and this passageway is filled with an absorbent material 51. Air inlet ports 52 are formed in the sides of the casing 48 above the bottom thereof and also above the level of the liquid fuel, 55 as hereinafter explained.

The operation of the burner is as follows: Liquid fuel is first admitted to the chamber 31 and is permitted to rise to substantially the level illustrated in Figure 8. The 60 oil is then ignited and after ignition, water is admitted through the pipe 29 and is permitted to rise to the top of the water jacket so that it will flow slowly through the ports 26 and gravitate down the inner face of the 65 cylindrical wall 16 of the combustion cham-

ber 15. Air is admitted through the stem 35 and will pass through the ports 41^a and 42. As the flame from the oil rises, it will be deflected or spread outwardly to the head 38 and against the wall 16, thereby contacting with the water flowing down the same and causing the vaporization of such water. As a consequence there will be a mixture of gaseous fuel, air and steam, resulting in a hot flame and complete combustion of the 70 fuel. This flame, of course, rises from the opening 23. If atmospheric air is desired it is only necessary to open the valve 45, whereupon such air will flow freely through the inlet port 44. If carburetted air is desired the valve 45 will be closed, whereupon the suction caused in the pipe 35 will result in an inflow of air through the ports 52, and this air passing through the absorbent material 51 in the carburetter casing, will 75 vaporize the liquid fuel that has been absorbed therein, carrying it through the pipe 47 and into the combustion chamber.

Referring now to Figure 1, there is disclosed therein the apparatus for supplying 90 fuel to the combustion chamber and carburetter and water to the water jacket, said apparatus affording an even and automatically controlled flow of the fluids and permitting an accurate adjustment of the levels 95 of said liquids. A liquid fuel reservoir is illustrated at 53, and preferably consists of an open tank, into which enters a fuel supply pipe 54 connected to an electric pump, illustrated diagrammatically at 55. The 100 operation of the pump 55 is controlled by the level of the fuel in the tank 53. To this end a portion of an electric circuit for operating the motor of the pump is shown at 56, and includes a circuit closer, comprising 105 a contact member 57 and a controlling arm 58 movable into and out of contact with said member 57. The member 58 has a link connection 59 with one arm of a lever 60 that is provided with a weighted arm 61. 110 This lever has also an arcuate actuating arm 62 extending on opposite sides of the fulcrum 63 of said lever. A plunger 64, in the tank 53, is carried by a lever 65 pivotally mounted between its ends, as shown at 115 66 on the tank 53. The lever projects beyond the tank and has a roller 67 that operates along the curved surface of the lever arm 62. With this construction when the tank 120 is full and the float in horizontal position, the roller 67 engaging the lower part of the arm 62 below the fulcrum 63, holds the control switch open, as shown, but when the level of the fuel falls the float moves downwardly with it, and after the roller 67 passes the fulcrum 63, it will strike the upper curved end of the arm 62 of the lever 60, as indicated in dotted lines. This will cause 125 said lever to move toward a position to close the switch 57-58, and after the weight 61 130

has been moved past the dead center, it will continue the movement of the lever 60 to effect such closure of the switch. This, as will be obvious, throws the pump 55 into 5 operation, and as the level of the fuel again rises, the float will again open the switch and stop the operation of the pump.

On a suitable support, shown at 68, is a fuel-level container in the form of a box 69, 10 and leading to this box 69, is a fuel supply pipe 70, forming the long leg of a siphon, the short leg 71 of which enters the reservoir 53, and preferably has a suitable strainer 72 on its intake end. At the top of the siphon 15 70—71 is a funnel 73 in communication with the long leg 70 of the siphon, said communication being controlled by a valve 74. The funnel preferably has a capacity about equal to the capacity of the long leg 70 of the siphon. From the box 69 extends the fuel-conducting pipe 32, which as already described, leads to the fuel reservoir 31 in the 20 burner shown in Figure 8. In said pipe 32 is located a controlling valve 75. Referring 25 now to Figures 3—7 inclusive, it will be noted that the outlet of the pipe 70, leading into the box 69, has mounted within said box a holding collar 76 provided with a valve seat 77, and said collar has also spaced depending ears 78. Pivotal mounted to and between said ears 78 is the ear 79 of an up-standing valve 80 that is movable into and out of cooperation with the seat 77. This valve is provided with oppositely extending 30 pins 81 and an upstanding arm 82 terminates in an abutment lug 83. A float 84, located in the box 69, is supported by an arm 85 preferably formed of two sections, as shown in Figure 4, said sections having their lower 35 portions separated, to form a yoke 86, and the lower end of the arms of this yoke are journaled on the ears 78 outside the same, the pivot pin for said arms being shown at 87 in Figure 3, and extending through the arms 86, the ears 78 and the ear 79. The top of the yoke extends over the arm 82 of the valve 80, and the abutment lug 83 of said arm is in the path of the arm 85. The arms 86 of the yoke have 40 upstanding lugs 88 that are adapted to engage the pins 81 on their outer sides. As clearly shown in Figure 3 the float controls the operation of the valve 80. When the level of the fuel is, as illustrated, the lugs 45 88 operating against the pins 81, hold the valve in its closed position. If the level falls the float moves downwardly with it, and if the valve does not open by reason of the pressure against its inner face, the arm 85 will engage the lug 83 and open it. From this box, the oil flows freely through the pipe 32 to the chamber 31 and combustion chamber 15 when the valve 75 is opened.

For the supply of fuel therefore in order 50 to start the siphon 70—71, the valve 75 is

closed and the funnel 73 filled with the fuel. The valve 74 is then opened and the long leg 70 of the siphon will be filled. The valve 74 is then closed and the siphon will operate. It will be understood that the container 69 70 is placed at the proper level, so that the fuel will flow freely into the chamber 31 and to substantially the level illustrated in Figures 8 and 11. Consequently not only will this fuel be in the combustion chamber, but also 75 in the lower portion of the carburetter and the operation above described will take place, fuel being supplied as rapidly as it is burned.

For the purpose of supplying the water to the water jacket, a reservoir 89 is provided, and a supply pipe 90 from any suitable source is connected thereto. The supply of water through the pipe is controlled by a valve 91 carried on the swinging arm 92 of a 80 float 93, so that the level in the reservoir 89 can be automatically maintained. From the reservoir 89 a siphon, comprising a short leg 94 entering into the reservoir and a long leg 95, is employed. The short leg 95 preferably has a suitable screen 96, and said siphon is provided with a starting funnel 97 and a controlling valve 98 which operates in the same manner as that already described 90 in connection with the fuel supply means. The leg 95 includes a flexible section 99 and a pipe 100 that is connected to another level-controlling container 101 arranged alongside the container 69. This container 101 is also 95 in the form of an open topped box having 100 a float valve preferably corresponding to that shown in Figures 3—7 inclusive. From the container or box 101 a flexible pipe 102 is connected to the pipe 29, and a controlling valve 103 is located at the juncture of said 105 pipes 29 and 102. The box 101, as clearly shown in Fig. 2, is vertically adjustable, any suitable means being provided for effecting this adjustment and holding it in adjusted 110 position. Thus in said figure a supporting screw is shown at 104, and is threaded through a sleeve 105 on the supporting table 68. The upper end of the screw has an operating handle 106 and is journaled in a bushing 107 carried by the under side of a 115 platform or shelf 108, on which the box 101 is mounted. This box can be placed at a height that will secure the desired level of the water in the water jacket of the burner, so that the water will rise to a height that 120 will permit its passage through the ports 26 into the combustion chamber, as already described, and yet will prevent an overpressure that might result in a surplus amount 125 of water being supplied to the combustion chamber. It also is useful in connection with different burners. For instance, the heights of the burners vary according to the size of the boiler or other heater and may range 130 from the shortest at two and one-half inches

to the tallest, four and three-quarters inches. These heights may be shown on the box 69 as indicated at 109, and the bottom of the container 101 can be placed at a height corresponding to the height of the burner used.

Briefly described, the operation of the apparatus is as follows: Fuel and water will be maintained respectively in the reservoirs 53 and 89 at a constant level, and this fuel and water will be delivered by gravity and at a constant pressure into the level-controlling tanks 69 and 101. From these tanks the fuel will enter the lower portion of the combustion chamber and burn, the combustion being assisted through the supply either of atmospheric air or carburetted air, as desired. During the initial stages water flowing from the water jacket will be transformed into steam within the combustion chamber and assist in securing complete combustion. Obviously as the burner becomes heated a portion of said water in said jacket will be transformed into steam and this steam will enter through the ports 26, and commingling with the uprising gaseous fuel and flames, will assist in combustion.

From the foregoing, it is thought that the construction, operation and many advantages of the herein described invention will be apparent to those skilled in the art, without further description, and it will be understood that various changes in the size, shape, proportion and minor details of construction may be resorted to without departing from the spirit or sacrificing any of the advantages of the invention.

Having thus fully described my invention, what I claim as new, and desire to secure by Letters Patent, is:—

40 1. The combination with a burner, of means for supplying by gravity a liquid fuel and water to the burner, comprising reservoirs for each, a water supply pipe connected to the water reservoir, a float-controlled valve for the water supply pipe, a siphon for withdrawing water from the water reservoir, said siphon having a short leg opening into the water reservoir and a long leg connected to the burner, a pump 45 for delivering liquid fuel to the fuel reservoir, float-operated pump controlling means

associated with the latter reservoir, and a siphon for withdrawing liquid fuel from the fuel reservoir and comprising a short leg opening into the fuel reservoir and a 55 long leg, said long leg being connected to the burner.

2. The combination with a burner, of liquid fuel and water reservoirs, conduits respectively supplying liquid fuel and water 60 from the reservoirs to the burner, containers in said conduits, through which the fuel and water pass, automatic supply controlling means in the containers, a common support for the containers, said containers being located side by side and means for mounting the containers and the controlling means therein on the support at relatively different heights to vary the respective levels of the fuel and water in the burner. 70

3. The combination with a burner, of liquid fuel and water reservoirs, conduits respectively supplying liquid fuel and water from the reservoirs to the burner, containers in said conduits, through which the fuel and water pass, automatic supply controlling means in the containers, said containers being located side by side and having means for indicating their respective elevations, and means for supporting the container of the water conduit and its controlling means at different heights to vary the height of the level of the water in the burner. 80

4. The combination with a burner, of liquid fuel and water reservoirs, means for supplying liquid fuel and water respectively to the reservoirs and automatically controlling the supplies, water and fuel containers respectively connected to the burner, 90 means for supporting the water container at different heights with respect to the fuel container and the burner, siphons for withdrawing the water and fuel from the reservoirs, and respectively delivering the same 95 to the containers, and automatic means controlling the passage of the liquids through the siphons to the containers.

In testimony whereof, I affix my signature.

GEORGE T. SMALLWOOD.
